UNITED STATES PATENT OFFICE.

JOHN H. GIBSON, OF BRUIN, PENNSYLVANIA.

TUBING ELEVATOR.

Application filed April 21, 1923, Serial No. 633,735. Renewed July 9, 1926.

The device forming the subject matter of this application is adapted to be used for holding tubing and the like, during the elevation, lowering and manipulating of the 5 tubing in well drilling operations. The structure comprises a pair of relatively movable jaws adapted to engage the tubing or other article, and one object of the invention is to provide a simple but efficient means 10 for latching the jaws securely but releasably in closed position.

It is within the province of the disclosure to improve generally and to enhance the utility of devices of that type to which the 15 invention appertains.

With the above and other objects in view, which will appear as the description proceeds, the invention resides in the combination and arrangement of parts and in 20 the details of construction hereinafter described and claimed, it being understood that, within the scope of what is claimed, changes in the precise embodiment of the invention shown can be made without departing from the spirit of the invention. 25

In the accompanying drawings:—

Figure 1 shows in elevation, a device constructed in accordance with the invention; Figure 2 is an elevation wherein the 30 device is viewed at right angles to the showing of Figure 1; Figure 3 is a section taken approximately on the line 3—3 of Figure 1; Figure 4 is a section taken approximately on the line 4—4 of Figure 1; and Figure 5 is a section taken approximately on the line 5—5 of Figure 4, parts being omitted; 35 and Figure 6 is a diagrammatic view illustrating the operation of the latch mechanism.

The device forming the subject matter of this application comprises a body, denoted generally by the numeral 1 and including jaws 2 and 3, provided at one end with knuckles 4, through which passes a pivot 40 element 5, the jaws 2 and 3 thus being so connected that they may be swung toward and away from each other, the opening movement of the jaws being limited by shoulders 6 located on the jaws, at the knuckles 4 thereof. Intermediate their ends, and upon their inner surfaces, the jaws 2 and 3 are supplied with grooves 7 which coact to form an opening 8 adapted to receive the tubing or other article. At one side of the 45 opening, the jaws 2 and 3 are cut away,

upon what may be denominated their upper surface, to form a notch or seat 9. Lugs 10 are formed on the jaws 2 and 3, on opposite sides of the line 11 where the jaws abut, the lugs being located close to the seat 60 or notch 9. A transverse recess 15 is fashioned in the jaws 2 and 3 at their free ends, the recess being in the lower portion of the jaws.

A bearing 16 is secured to the outer surface of the jaw 2 adjacent to the free end thereof. A loop-shaped keeper 17 is provided, the same including an end 18, an end piece 19, and side pieces 20 and 21, the side piece 20 being straight, and the side 65 piece 21 being curved slightly. The end piece 19 is mounted for rocking movement in the bearing 16 and is received somewhat loosely in the bearing, so that the end piece 70 may tilt in the bearing, out of parallelism with the axis of the bearing, as shown in Figure 6, Figure 6 being a diagrammatic view wherein the tilting of the part 19 is exaggerated, in order to bring out a feature 75 of operation hereinafter described. A finger 22 projects from the side piece 20 of the keeper 17 and is adapted to enter the seat 9, the finger being supplied in its under surface with a recess 23 adapted to receive the lugs 10 on the jaws 2 and 3. 80

A longitudinal recess 25 is formed in the jaw 2 at the free end thereof. The numeral 26 marks a hook-shaped latch which is resilient, one end of the latch being secured to the inner surface of the jaw 3 at the free 85 end thereof, the latch comprising an inclined arm 27 having a shoulder 28 provided with an inset end 29 mounted slidably on a headed stop pin 30 carried by the jaw 3, the stop pin serving to limit the outward swinging movement of the spring arm 27.

The jaws 2 and 3 are equipped with outstanding circumferentially grooved knobs 31 on which the lower ends of loop-shaped suspension elements 32 are mounted, the suspension elements being held on the knobs by bearings 33, disposed between the side portions of the suspension elements. The bearings 33 have outstanding projections 34 mounted to move in notches 35 formed on the peripheries of the knobs 31, the notches 35 being of such circumferential extent that the body 1 may be swung on the suspension elements 32 through an angle of approximately 90° ninety degrees, thereby to permit the tubing 110

or other article which is carried between the jaws 2 and 3 to be disposed either in a vertical position or in a horizontal position.

A glance at the drawings taken in connection with the foregoing description, will render clear to those skilled in the art, the general operation and functions of such parts as the body 1, the suspension elements 32 and the like, it being clear that the jaws 2 and 3 10 may be opened and closed to receive the tubing or other article.

The device, however, is characterized by a peculiar operation which takes place in connection with the keeper 17, and this operation now will be set forth.

When the keeper 17 is swung around toward the locked position shown in Figure 3, the arm 27 of the spring latch 26 is pressed inwardly by the end piece 18 of the keeper. 20 The finger 22 on the side piece 20 of the keeper thus rides up on the inclined surfaces of the lugs 10 of the jaws 2 and 3, as shown in Figure 6, the result being that the keeper is tilted in the bearing 16 in the direction of the arrow A in Figure 6, the tilting of the keeper being exaggerated in that figure for the sake of illustration. The free end of the finger 22 ultimately passes over the lugs 10 and, since the shoulder 28 on the arm 27 of 30 the latch 26 tends to exert a pressure in the direction of the arrow B in Figure 6, at right angles to the axis of the bearing 16, the end piece 19 of the keeper is straightened up, until it stands parallel with the axis of the bearing 16, the free end of the finger 22 moving downwardly in the direction of the arrow C, and the lugs 10 on the jaws 2 and 3 35 being received in the recess 23 of the finger 22. The result is that the jaws 2 and 3 are held by a double lock, the end piece 18 of the keeper 17 preventing the jaws from opening, and the lugs 10 of the jaws being received in the recess 23 of the finger 22, the shoulder 28 on the latch 26 engaging with the end piece 18 of the keeper as shown in Figure 3 40 to prevent the keeper from opening.

What is claimed is:—

1. A device of the class described compris-

ing jaws having knobs, means for pivotally connecting the jaws, loop-shaped suspension elements receiving the knobs, and bearings in the suspension elements and cooperating with the knobs, the bearings and the knobs having cooperating elements which limit the swinging movement of the suspension elements to a predetermined arc on the knobs.

2. A device of the class described comprising jaws having outstanding knobs supplied with circumferential grooves, means for connecting the jaws pivotally, loop-shaped suspension elements received in the grooves of the knobs, bearings mounted in the suspension elements, and having outstanding projections, the bearings coacting with the knobs to retain the suspension elements thereon, and the knobs being supplied with peripheral notches wherein the projections of the bearings have limited movement circumferentially of the knobs.

3. In a device of the class described, a pair of pivotally connected jaws, a keeper receiving one jaw and mounted to swing on the other jaw, the keeper and one jaw having interengaging elements, the keeper being tiltable from an original position to permit said interengaging elements to pass each other, and spring means for tilting the keeper back to said original position to cause said elements to interengage after the keeper has been swung to closed position.

4. In a device of the class described, a pair of pivotally connected jaws, a keeper receiving one jaw and mounted to swing on the other jaw, the keeper on one jaw having interengaging elements, the keeper being tiltable from an original position to permit said interengaging elements to pass each other, and spring means for tilting the keeper back to said original position to cause said elements to interengage after the keeper has been swung to closed position, said spring means comprising a part coacting with the keeper to hold the keeper in closed position.

In testimony that I claim the foregoing as my own, I have hereto affixed my signature.

JOHN H. GIBSON.
